TRANSISTOR UNIT

George W. S. Fogg, Phoenix, Ariz., assignor to Motorola Inc., Chicago, Ill., a corporation of Illinois

Application June 5, 1953, Serial No. 359,933

6 Claims. (Cl. 317—235)

The present invention relates to circuit elements and more particularly to an improved point contact transistor unit.

The usual known type of point contact transistor comprises a semi-conductive block composed, for example, of a germanium crystal, and the transistor also includes a pair of pointed fine wire or ribbon electrodes supported to extend in spaced parallel relation against one face of the block. These electrodes constitute respectively the emitter and collector for the transistor. The transistor also includes a base electrode which usually takes the form of a metal tab soldered to an opposite face of the germanium block.

The cubical dimension of the germanium block is of the order of .032" on a side, and the fine wire electrodes are about .005" in diameter with a spacing at their points of about .002". It is obvious that the dimensions and spacings of these components are entirely too small to lend themselves to production methods involving any but the most highly skilled labor. The fabrication of point contact transistors using such microscopic components, therefore, is slow and arduous and is accompanied by a high percentage of rejections, which result in an unduly high cost for the individual units. In addition to the difficulties encountered in the manufacture of this type of point contact transistor, the resulting units are fragile and delicate and are incapable of withstanding rough usage.

It is, accordingly, an object of the present invention to provide a new and improved point contact transistor unit which is devised so that its various components may be manufactured mechanically and which may be assembled without the need for an undue amount of skilled labor.

A further object of the invention is to provide an improved transistor unit that may be constructed simply and expeditiously and which is relatively rugged and efficient in operation.

A feature of the invention is the provision of an improved circuit element in the form of a transistor unit which utilizes preformed metallic strips for the various electrodes, and which strips are mounted rigidly and securely on an insulating base with a semi-conductive block soldered to one end of one strip and with the edges at the ends of the other strips in resilient point contact with an edge of the block.

Another feature of the invention is the provision of such an improved point contact transistor unit in which a plurality of preformed metallic strips are securely supported on an insulating base, with a semi-conductive block supported at the end of one of the strips, with the other strips having spaced knife edges in resilient contact with an edge of the block, and in which the critical dimensions between such edges is established by an insulating spacer to obviate the need for difficult manual spacing.

The above and other features of the invention which are believed to be new are set forth with particularity in the appended claims. The invention itself, however, together with further objects and advantages thereof, may best be understood by reference to the following description when taken in conjunction with the accompanying drawing in which:

Figure 1 shows one embodiment of the invention; and Figure 2 is a fragmentary view of an end portion of the unit of Figure 1.

The transistor unit of the present invention comprises

2

a flat insulating base member having a pair of ends with a centrally located longitudinal slot at one end. A pair of resilient metallic strips is mounted in spaced relation on the base, and these strips extend upwardly at an angle to the top surface of the base from one end of the base toward the other. The end portions of the strips extend inwardly across the base toward one another and each end portion has a bent-over extremity extending downwardly toward the surface of the base. These extremities are spaced and parallel to one another and terminate in a pair of spaced knife edges facing the base. A third electrically conductive strip is mounted on the base and extends along the top surface of the base from one end toward the other between the pair of strips referred to above. The third strip has a portion extending into and along the slot in the base and has an extremity extending upwardly toward the edges of the pair of strips referred to previously and at a selected angle thereto. A block of semi-conductive material is affixed to the extremity of the third strip and has an edge in resilient point contact with the knife edges of the first pair of strips.

The transistor unit of the present invention, as illustrated in the drawing, includes a flat insulating base 10 which may be composed, for example, of a molded plastic material such as phenolic. The base, for example, may be .062" thick, .625" long and .312" wide. The base has an aligned series of rectangular apertures 11, 12 and 13 disposed adjacent and parallel to one end thereof. A pair of resilient metallic strips 14, 15 are swedged in the outer apertures 11 and 13 and extend from one end of the base to the other in spaced parallel relation and inclined at an angle to the top surface of the base. Strips 14 and 15 have respective end portions 16 and 17 which extend inwardly across the base toward one another. The end portions 16 and 17, in turn, have bent-over extremities 18 and 19 which extend downwardly toward the top surface of base 10 and which are terminated in individual spaced knife edges 20 and 21. The extremities 18 and 19 are parallel to each other and are spaced by a selected amount by an insulating spacer 22.

The metallic strips referred to above may, for example, be composed of Phosphor bronze or of beryllium copper of No. 4 hardness, or of any other suitable resilient electrically conductive material. Insulating spacer 22 may be an accurately gauged piece of mica having a thickness, for example, of .002". The spacer insulates the extremities 18 and 19 from one another and separates knife edges 20 and 21 a microscopic amount without the need for any precise manual adjustment. The metallic strips themselves may be of the order of .005" thick and .062" wide.

A third resilient metallic strip 23 is anchored in the intermediate aperture 12 by swedging and extends along the top surface of base 10 between strips 14 and 15 and parallel thereto. Strip 23 extends downwardly into a central slot 27 provided at the other end of base 10 and has an end portion 28 extending along that slot with an extremity extending upwardly toward the knife edges 20 and 21 at a selected angle thereto. The strips 14, 23 and 15 have respective end portions 24, 25 and 26 extending beyond the end of base 10 to constitute terminals for the transistor.

A rectangular block of semi-conductive material 29, such as a germanium crystal, is soldered to the extremity 30 of end portion 28 and is supported by the extremity to have an edge in resilient point contact with the respective knife edges 20 and 21. With the illustrated construction, the extremity 30 of metallic strip 23 constitutes a base electrode for the semi-conductive block 29, and electrical connection is made to the base through metallic strip 23 and end portion 28 from terminal 25. The knife edges 20 and 21 of metallic strips 14 and 15 form the emitter and collector electrodes for block 29, and electrical connection is made to these latter electrodes through strips 14 and 15 respectively from their terminals 24 and 26.

The various metallic strips may be punched and pre-formed by well-known mechanical processes and may be provided with appropriate ears which are swedged into the bores of apertures 11, 12 and 13. The mounting of

the strips on base 10 is not unduly critical since manufacturing tolerances are absorbed by the resilient nature of the ends of the various strips. Accurate spacing between knife edges 20 and 21 is achieved by the simple expedient of interposing the insulated spacer 22 between the bent-over extremities 18 and 19. The resulting unit is relatively rugged since its various metallic components are rigidly and securely anchored in base 10 and the semi-conductive unit 29 is soldered or otherwise securely affixed to the end of strip 23 and firmly held against knife edges 20 and 21.

The transistor unit may be coated with a moisture proof coating such as a non-hygroscopic oil, and the unit may then be sealed in a suitable capsule. The knife edges 20 and 21 contact the edge of the crystal block at spaced points along the latter edge and may be sharpened, either mechanically or by means of an etching process to a width of the order of ".0001".

The invention provides, therefore, an improved and rugged transistor unit that may be constructed simply and without the need for critical manual spacing and assembling of microscopic fine wire or cat-whisker electrodes. The unit of the invention lends itself to mechanical formation of the various metallic strips by punching, shearing, die-cutting and the like, and the various strips may be assembled on the base and accurately placed in contact with the crystal without the need for delicate manual spacing and mounting operations.

Moreover, the unique construction of the improved transistor unit of the present invention permits the use of relatively large resilient metallic strips, thereby simplifying handling and facilitating production methods. The particular mounting of the resilient strips on the base provides uniform contact point pressure for each transistor unit and for successively produced units. This is because the contact pressure is established by the resilience of the strips themselves in conjunction with precisely located anchoring points for the strips on the base.

While a particular embodiment of the invention has been shown and described, modifications may be made and it is intended in the appended claims to cover all such modifications as fall within the true spirit and scope of the invention.

I claim:

1. A transistor unit including in combination, a flat insulating base member having a pair of ends and a centrally located longitudinal slot adjacent one of said ends, a pair of resilient electrically conductive strips mounted in spaced relation on a surface of said base and extending at an angle to said surface from one end of said base toward the other, said strips having end portions remote from said one end of said base extending inwardly toward one another and said end portions having bent-over extremities extending downwardly toward said surface of said base, said extremities being spaced one from the other and terminating in a pair of spaced edges facing said base, a third resilient electrically conductive strip mounted on said base and extending along said base from said one end toward said other end intermediate said pair of strips, said third strip having a portion extending into and along said slot in said base and said portion of said third strip having an extremity extending upwardly toward the aforesaid edges of said extremities of said pair of strips at a selected angle thereto, and a block of semi-conductive material affixed to said extremity of said portion of said third strip and having an edge in point contact with each of said edges of said extremities of said pair of strips.

2. A transistor unit including in combination, a base member, a pair of electrically conductive strips mounted on said base and inclined at an angle to a surface of said base, said strips having end portions extending downwardly toward said surface of said base in spaced and parallel relation, said end portions terminating in a pair of spaced edges, a third resilient electrically conductive strip mounted on said base and extending along said base, said third strip having an end portion extending upwardly toward the aforesaid pair of edges at a selected angle thereto, and a block of semi-conductive material affixed to said end portion of said third strip and having an edge in point contact with each of said pair of edges of said first-mentioned pair of strips.

3. A transistor unit including in combination, a base member having a longitudinal centrally located slot therein in adjacent one end of said base, a pair of spaced electrically conductive resilient strips anchored to a surface of said base and extending toward said one end from said other end of said base at an angle to said surface, said strips having end portions extending downwardly toward said surface of said base in spaced parallel relation and said end portions terminating in a pair of spaced edges, a third resilient electrically conductive strip anchored to said surface of said base and extending along said base toward said one end from said other end of said base and extending into and along said slot, said third strip having an end portion extending upwardly toward the aforesaid pair of edges at a selected angle thereto, and a block of semi-conductive material affixed to said end portion of said third strip and having an edge in resilient point contact with each of said pair of edges of said first-mentioned pair of strips.

20 4. A transistor unit including in combination, an insulating base member having a longitudinal centrally located slot therein at one end of said base, a pair of spaced parallel resilient metallic strips anchored to a surface of said base and extending toward said one end from the other end of said base at an angle to said surface, said strips having end portions extending inwardly toward one another and said end portions having bent-over extremities extending downwardly toward said surface of said base, said extremities being spaced and parallel one to the other and terminating in a pair of spaced knife edges facing said base, a third resilient metallic strip anchored to said surface of said base and extending along said surface of said base toward said one end from said other end of said base and extending into and along said slot, said third strip having an end portion extending upwardly toward the aforesaid pair of edges at a selected angle thereto, and a block of semi-conductive material affixed to said end portion of said third strip and having an edge in resilient point contact with each of said pair of edges of said first-mentioned pair of strips.

5. A transistor unit including in combination, a base member having a pair of ends and having at one end a central longitudinal slot, a pair of spaced parallel resilient metallic strips anchored to a surface of said base and extending from the other end of said base toward said one end at an angle to said surface, said strips having end portions extending inwardly toward one another and said end portions having bent-over extremities extending downwardly toward said surface of said base, said extremities being parallel one to the other and terminating in a pair of spaced knife edges facing said base, an insulating spacer interposed between said extremities to insulate said strips one from the other and to space said edges by a selected amount, a third resilient metallic strip anchored to said surface of said base and extending along said base toward said one end thereof and into and along said slot, said third strip having an end portion extending upwardly toward the aforesaid pair of knife edges at a selected angle thereto, and a block of semi-conductive material affixed to said end portion of said third strip and having an edge in resilient point contact with each of said pair of knife edges.

6. A transistor unit including in combination, a base member, a pair of electrically conductive strips mounted on said base, said strips having adjacent end portions spaced from one another and terminating in a pair of spaced edges, a third resilient electrically conductive strip mounted on said base and having an end portion adjacent said pair of edges, and a block of semi-conductive material in contact with said third strip and having an edge in point contact with each of said pair of edges of said first-mentioned pair of strips.
